UNITED STATES PATENT OFFICE.

WILLIAM B. SCAIFE, OF PITTSBURG, PENNSYLVANIA.

CAR-TRUCK.

SPECIFICATION forming part of Letters Patent No. 745,119, dated November 24, 1903.

Application filed May 15, 1903. Serial No. 157,208. (No model.)

To all whom it may concern:

Be it known that I, WILLIAM B. SCAIFE, of Pittsburgh, Allegheny county, Pennsylvania, have invented a new and useful Car-Truck, 5 of which the following is a full, clear, and exact description, reference being had to the accompanying drawings, forming part of this specification, in which—

Figure 1 is a side elevation of the blank for the side frame, showing in dotted lines the contour after pressing. Fig. 2 is a top plan view of the pressed side frame. Fig. 3 is an inner side elevation of the pressed frame. Fig. 4 is a bottom plan view of the frame. 15 Fig. 5 is a side elevation, partly broken away, of the completed side frame. Fig. 6 is a transverse vertical section, the left half being taken through a pedestal and the right half through the transom; and Fig. 7 is a top plan view of 20 the truck-frame with the left-hand half in horizontal section.

My invention relates to the class of pedestal car-trucks, and is designed to provide a truck-frame composed partly of pressed-steel 25 shapes and partly of rolled shapes, such as angles, which shall be of great strength and may be readily and rapidly made. It is also designed to provide a side frame which shall have great stiffness against lateral bending 30 strains.

In the drawings, Fig. 1 shows the blank from which the body of the side frame is 35 pressed up. This blank 2 is provided with vertically-extending slots 3 near each end, the upper corner 4 being rounded off. This blank is heated and placed in a press, in which it is shaped into the side frame body member (shown in Figs. 2, 3, and 4) by bending the blank on the dotted lines of Fig. 1. The 40 upper portion of the blank is bent into a wide top flange 5, which gradually tapers in width through the portions 6 to the narrower portions 7 of the pedestal. The lower part of the blank is bent into a narrower flange 8, 45 the end portions of which taper toward the plane of the blank, as shown in Fig. 4. The body 2 is narrowest at the central portion, its end portion gradually enlarging through the parts 9 to the pedestals. The flanges 7 are 50 continued at 7' down along the outer leg of each pedestal, and the pedestal-opening is also provided with side flanges 10 and 11, which

are joined together at the top by the flange 12. By reference to Fig. 4 it will be seen that all of the flanges produced by pressing up the blank 55 extend inwardly and in the same direction at right angles to the plane of the blank-body. After the blank is thus pressed up an angle is riveted along its outer face, this angle extending from one pedestal to the other and 60 forming tension members in its intermediate portions. The outer portion 13 of this angle extends along the outer leg of the pedestal, thence over the top of the pedestal at 14, and thence downwardly and inwardly to the portion 15 to the point *a*, where the flange 8 of the pressed blank begins to converge toward the pedestal. The angle is continued through the horizontal portion 16 to the similar point *a* on the other side of the transom and thence 65 through the successive portions 15, 14, and 13. The flange 17 of this angle projects outwardly in the opposite direction to the pressed flanges of the side frame. The two flanges 17 and 10 combine to form a broad flat face 70 along the outside of the pedestal-opening, and on these flanges is mounted the wearing-plate 18. To support the inner wearing-plate 19, I rivet a vertical angle 20 along the inner side of the pedestal-opening, this merely extending up to the inclined portion 15 of the continuous angle. The pedestal tie-bars are 75 shown at 21. The inclined portions 15 of the continuous angle extend from the top of the pedestal downwardly and inwardly to the 80 lower edge of the transoms, substantially in line with the strains coming to the transom and passing to the pedestals. There is therefore no bending movement upon these inclined portions, which form true tension members. 85

The transom is shown as composed of two pressed channels 22, placed in parallelism, with their flanges 23 and 24 extending outwardly. The end of each channel is secured 90 to the side-frame web by a pair of angles 25, as shown in Fig. 7, and the securing-rivets for these angles extend through a strengthening-plate 26, covering the inner face of the web of the side frame in the central portion. 95 This strengthening shape is preferably rectangular in shape, as indicated in Figs. 5 and 7. The wide top flange 5 of the side frame lies on the top flanges 27 of the transom-chan-

nel and is riveted thereto. The lower flanges 24 are correspondingly riveted to the flange 8 of the side frame.

It will be noted that the pressed flanges 7' 5 are of considerable depth and stiffen the ends of the pedestals laterally. The flanges projecting in opposite directions from the vertical plane of the web—on the inner side of the pressed-up flanges and on the outer side the 10 angle-flanges—give great stiffness against lateral strain.

The advantages of my invention result from the combining of the pressed flanged blank with the flanged shape which is secured thereto. 15 Great stiffness is afforded, the construction is simple and easily made, and the advantages of structural shapes and pressed shapes are combined.

Many variations may be made in the form 20 of the pressed blank, the rolled shape riveted thereto, the arrangement of the pedestals and wear-plates, &c., without departing from my invention.

I claim—

25 1. A truck side frame having a pressed-plate body with pedestal-openings, and an outer flange extending alongside said openings, and a longitudinally-extending flanged shape riveted to the web of the pressed body, 30 with its flange projecting in the opposite direction to that of the body-flange; substantially as described.

2. A truck side frame having a pressed-plate body with substantially continuous edge 35 flanges projecting laterally, and a longitudinal flanged shape riveted to the body with its flange projecting in the opposite direction to that of the pressed flanges; substantially as described.

3. A truck side frame consisting of a pressed-steel body with edge flanges and a continuous flanged shape riveted to the vertical web 40 of the body and having inclined portions extending from the tops of the pedestals downwardly toward the lower part of the transom; substantially as described.

4. A truck side frame having a pressed-steel body with an inwardly-projecting flanges surrounding the pedestal-opening, a longitudi-

nal flanged shape having its end portion extending down the outer pedestal-leg, the flange of said shape projecting in the opposite direction from the pressed flange on the body; substantially as described. 50

5. A truck side frame comprising a pressed-steel body with inwardly-projecting flanges surrounding the pedestal-opening, a continuous longitudinal angle having the flanges of its end portions projecting outwardly along the outer leg of the pedestal, and short vertical angles secured along the inner face of the pedestal-opening with their flanges projecting outwardly; substantially as described. 55

6. A truck side frame having a body composed of a pressed-steel blank with substantially continuous edge flanges extending around its margin and around the pedestal-openings; and a flanged shape riveted to the body with its flange projecting in the opposite direction to that of the pressed flanges; 60 substantially as described. 65

7. A truck having a pressed-steel side frame, a strengthening-plate in its central portion, and a transom having its members secured to the side frame by pairs of angles, the securing-rivets extending through the strengthening-plate; substantially as described. 75

8. A pressed-steel side frame having pressed flanges, and a continuous angle extending over both pedestals and thence downwardly and inwardly to and along the under part of the transom-juncture; substantially as described. 80

9. A truck side frame having a pressed-plate body with edge flanges projecting laterally in the same direction, and a longitudinally-extending flanged shape riveted to the web of the pressed body with its flange projecting in the opposite direction to that of the body-flanges; substantially as described. 85 90

In testimony whereof I have hereunto set my hand.

WM. B. SCAIFE.
